UNITED STATES PATENT OFFICE.

EDWARD J. JACKOBOICE, OF GRAND RAPIDS, MICHIGAN.

ROAD SCRAPER.

Application filed September 7, 1926. Serial No. 133,785.

The present invention relates to road scrapers; and its object is to provide a road scraper having a scraper blade and improved means for changing the angle thereof relatively to the direction of the machine's travel over the road.

This and any other and more specific objects hereinafter appearing are attained by, and the invention finds preferable embodiment in, the structure hereinafter particularly described in the body of this specification and illustrated by the accompanying drawings, in which:

Figure 1 is a top plan view of a portion of a wheeled vehicle having a road scraper mounted thereon, certain parts being sectioned horizontally on line 1—1 of Figures 2 and 3;

Figure 2 is a left-hand side view thereof, a shaft being sectioned vertically on line 2—2 of Figure 1;

Figure 3 is a front view of certain parts of the machine;

Figure 4 is a vertical sectional view of certain parts taken on line 4—4 of Figure 2;

Figure 5 is a top plan view of certain parts mounted at the left-hand side of said vehicle, and illustrating a modified construction;

Figure 6 is a face view thereof, showing the parts in another position and sectioned on line 6—6 of Figure 7;

Figure 7 is a front view of said parts, partially sectioned on line 7—7 of Figure 6;

Figure 8 is a top plan view of certain parts of the machine, illustrating another modified construction; and

Figure 9 is a left-hand side view of the same.

In the embodiment of the invention chosen for illustration by the accompanying drawings and for detailed description in the body of this specification, a road scraper is shown of the same type as that illustrated and described in my Patent No. 1,478,436, issued December 25, 1923.

The present invention consists in the novel means whereby the scraper blade of the machine is turned to, and held in, a desired angle relatively to the direction of the machine's travel over the road.

In the accompanying drawings, the road scraper mechanism is mounted on a vehicle—a motor truck or the like—having the frame 1 and rear or traction wheels 2. The bearing blocks or swingable arms 3 (shown in Figures 1, 2, 4, 5, 6 and 7) are pivotally mounted at 18

on vertical axes on the opposite sides respectively of the frame. These bearing blocks or swingable arms 3 have axially vertical bearings 4 in which the spindles 5 of the bearing members 6 may turn, and may also be moved vertically to fixed positions in which they may be clamped as by the screw bolts 7. These bearing members 6 have horizontally disposed bearings 8 in which turns a horizontally disposed shaft 9 carrying the scraper blade 10. This scraper blade is thus carried by means of collars 11 turnably adjustable to fixed positions on the shaft by clamping screws 12, the scraper blade being supported on the collars by means of its upright posts 13 turnably mounted on the collars at 14. The scraper blade is yieldingly held relatively to the collars by springs 15, 16 coiled around rods 17 carried by the collars and passing freely through openings in the scraper blade, said springs pressing against the opposite sides respectively of the scraper blade, their tension being adjustable by the nuts 19 threaded on said rods. It will be seen that the scraper blade is thus held yieldingly balanced by the springs 15 and 16 and may thus yield forwardly or rearwardly in its contact with the surface of the road being operated on.

The scraper blade may be tilted to a desired angle about the axis of the shaft 9 by rocking the shaft in its bearings 8 by suitable means, as by turning the upright shaft 21 (provided with a suitable hand wheel not shown), journaled at 22 on the vehicle's frame and having a worm 23 meshing with a toothed segment 24 pivoted at 25 on the frame and pivoted eccentrically at 26 to a connecting rod 27 whose rear end is loosely pivoted at 28 on an arm 29 of a sleeve 30 on the shaft 9, said sleeve being adjustable by its clamping screw bolt 31 in fixed positions on the shaft. The connecting rod 27 may be sufficiently springable to permit the swinging of the scraper blade to the desired angular position relatively to the frame of the vehicle.

In order that the horizontal angle between the scraper blade and the direction of the travel of the vehicle over the road may be changed as desired, one or both of the bearing blocks 3 may be swung on their pivotal mountings 18 to positions indicated in Figures 1 and 5, so that the scraper blade may extend at right angles to said direction of travel or be inclined either way from said direction, the shaft 9 in making such adjustments sliding

in its bearings 8; and these bearing blocks 3 may be secured in certain positions by the screw bolt 50 threaded at 51 in the frame, or as seen in Figures 5, 6 and 7 by a detent or 5 pin 52 thrust through the hole 53 in said block and any of the holes 54 in the sector 55 secured at the side of the frame.

In the modified construction shown in Figures 8 and 9, the bearing blocks 3¹ instead of 10 being swingably mounted are slidable in the vehicle's longitudinal direction in bearings 65 by screw shafts 57, 58 respectively threaded in said blocks and journalled at 59, 60 on the frame. These shafts have gears 61 meshing with the gears 62 on the transverse shaft 63 which may be turned by its crank wheel 64 to move one of said blocks forwardly and the other rearwardly. These blocks may be 15 additionally held in position by set screws 56.

20 The connecting rod 27 is provided with suitable means for accommodating it to changed angular positions of the scraper blade relatively to the longitudinal direction of the frame 1. This purpose may manifestly 25 be accomplished in various ways, one such way being shown in my said patent. Another way shown in Figure 2 of the present application's drawings, is the provision of spaced openings 66 in said rod, into any one of which 30 the pivot pin 26 may be inserted. A brace rod 67 serves to securely hold the pivot post 25 against lateral movement at its outer end.

From the foregoing description, the operations of my road scraper will be readily understood, viz: The scraper blade may be bodily raised or lowered by means of the spindles 5 vertically adjustable in the bearings 4; the scraper blade may be inclined at a desired angle to the direction of the vehicle's travel 40 by swinging one or both of the bearing blocks 3, or by sliding the bearing blocks 3¹ by the screw mechanism turned by the shaft 63; the scraper blade may be tilted on the axis of the shaft 9 by the worm and segment mechanism 45 connected to the sleeve 30; this sleeve and also the collars 11 may be adjusted to desired turned positions on the shaft 9 by their clamping screws; the scraper blade is yieldingly balanced against rearward and forward turning 50 movement on its pivotal mounting 14 by the springs 15 and 16.

The invention being intended to be pointed out in the claims, is not to be limited to or

by details of construction of the particular embodiment thereof illustrated by the drawings or hereinbefore described. 55

I claim:

1. In combination with a vehicle having a frame, a road scraper comprising: an arm swingably mounted on a vertical axis adjacent one side of the frame; a scraper blade carried adjacent the opposite side of the frame and by the free end of the arm and being otherwise unconnected to the frame and freely movable relatively thereto. 60

2. In combination with a vehicle having a frame, a road scraper comprising: an arm swingably mounted on a vertical axis adjacent one side of the frame; a scraper blade carried adjacent the opposite side of the frame 70 and by the free end of the arm and being otherwise unconnected to the frame and freely movable relatively thereto; means for holding the arm in swung positions.

3. In combination with a vehicle having a frame, a road scraper comprising: bearing blocks swingably mounted on vertical axes adjacent the opposite sides respectively of the frame; a scraper blade carried turnably on vertical axes by the free ends of said blocks 80 and being otherwise unconnected to the frame and freely movable relatively thereto.

4. In combination with a vehicle having a frame provided with a vertical bearing adjacent one side, a road scraper comprising: 85 an arm swingably mounted on a vertical axis adjacent the opposite side of the frame and having a vertical bearing; a scraper blade having spindles turnable in said bearings and being otherwise unconnected to the frame 90 and freely movable relatively thereto.

5. In combination with a vehicle having a frame, a road scraper comprising: an arm swingably mounted on a vertical axis adjacent one side of the frame; a scraper blade 95 carried at one of its ends adjacent the opposite side of the frame and at its other end by the free end of the arm and being otherwise unconnected to the frame and freely movable relatively thereto and being slidably 100 carried at one of its ends.

In testimony whereof I have hereunto set my hand at Grand Rapids, Michigan, this 31st day of August, 1926.

EDWARD J. JACKOBOICE.
